Des. 228,011
Patented July 31, 1973

228,011

MACHINE FOR LOADING AND STACKING CROPS

Allen A. White, Peabody, Harold Keith Garrison, Newton, and Gary Weddle, Wichita, Kans., assignors to Hesston Corporation, Hesston, Kans.

Filed May 3, 1971, Ser. No. 139,991

Term of patent 14 years

Int. Cl. D15—03

U.S. Cl. D40—1 E

Fig. 1.

Fig.2.

Fig. 4.

Fig. 3.

Fig. 5.

Fig. 6.

Fig. 7.

FIG. 1 is an elevational view showing one side of a machine for loading and stacking crops embodying our present design;

FIG. 2 is an elevational view showing the opposite side thereof;

FIG. 3 is a front elevational view thereof;

FIG. 4 is a rear elevational view thereof;

FIG. 5 is a top plan view thereof;

FIG. 6 is a perspective view as seen from the front of FIG. 1; and

FIG. 7 is a perspective view as seen from the rear of FIG. 1.

We claim:

The ornamental design for a machine for loading and stacking crops, as shown.
